UNITED STATES PATENT OFFICE

172,299

COMBINED PICTURE FRAME AND PLANTER

Benjamin Parker, Pasadena, Calif.

Application July 13, 1953, Serial No. 25,905

Term of patent 7 years

(Cl. D35—3)

To all whom it may concern:

Be it known that I, Benjamin Parker, a citizen of the United States of America, resident of Pasadena, in the county of Los Angeles, State of California, have invented a new, original, and ornamental Design for a Combined Picture Frame and Planter, of which the following is a specification, reference being had to the accompanying drawings, forming a part thereof.

In the drawing,

Fig. 1 is a front elevation view of the combined picture frame and planter, showing my new design;

Fig. 2 is a plan view of the combined picture frame and planter.

Fig. 3 is an end elevational view;

Fig. 4 is a fragmentary sectional view taken on the line 4—4 of Fig. 2; and

Fig. 5 is a partial plan view of the right-hand extremity of Fig. 2 with the planter receptacle removed to show the configuration of the outer end of the supporting base.

I claim:

The ornamental design for a combined picture frame and planter, as shown.
